UNITED STATES PATENT OFFICE

PERCY HULBURD, OF LONDON, ENGLAND.

APPARATUS FOR REMOVING SEDIMENT FROM STEAM-BOILERS.

No. 895,182.

Specification of Letters Patent

Patented Aug. 4, 1908.

Application filed June 24, 1907. Serial No. 330,614.

To all whom it may concern:

Be it known that I, PERCY HULBURD, a subject of the King of Great Britain, residing at 150 Leadenhall street, London, England, 5 have invented new and useful Improvements in Apparatus for Removing Sediment from Steam-Boilers, of which the following is a specification.

My invention relates to mechanical boiler 10 cleaning apparatus of the kind described in the specification of former United States Letters Patent No. 632,785 of 1899 wherein the use of draw-off heads is described, each of which is formed with a series of inclined openings through which the scum or other impurities are removed or blown off. Hitherto these draw-off heads have been made rigid and have had to be specially adapted to the 15 particular situations in which they are to be fixed.

The object of my invention is to provide an apparatus which may be readily adapted to any desired shape or contour according to the position in which it is to be placed and to 20 this end my invention consists in the use of flexible draw-off heads.

In practice I make use of spirally wound 25 metallic tubing and I provide for attaching to or forming upon the convolutions thereof 30 nozzles having inclined openings which correspond with the openings hitherto cast in the draw-off heads. With this arrangement it will be understood that the draw-off head can be made of any desired length and bent 35 in any desired manner according to requirements.

To enable my invention to be fully understood I will describe the same by reference to the accompanying drawings, in which:—

40 Figure 1 is a sectional plan of a locomotive fire box provided with my improved sediment remover, and Fig. 2 is a sectional side view of the same. Fig. 3 is a sectional view of a nozzle. Fig. 4 is a sectional plan of a combined joint and nozzle shown in Fig. 1 drawn 45 to an enlarged scale, and Figs. 5 and 6 are respectively an end view and a longitudinal section of one portion of the same. Fig. 7 is a view similar to Fig. 5 of another portion of 50 the said joint. Figs. 8 and 9 are respectively an end elevation and a longitudinal section of an end nozzle. Fig. 10 is a side view of the draw-off connections, and Fig. 11 is a section on the line 11—11, Fig. 10.

55 *a, b* indicate the two walls of the fire box and *c, c* are flexible tubes which are inserted

into the space between the said walls, the said tubes being advantageously made of spirally wound metallic tubing and having fixed upon them a series of nozzles or draw-off heads *d* 60 each of which has on the underside a nozzle *e* which forms a foot for supporting the tube and which has an inclined mouth *f* through which, when the tubes are open to the atmosphere by a blow-off cock the sediment 65 will be discharged with the water by the pressure of steam within the boiler, as described in the former specification.

It will be understood that a flexible pipe, 70 provided with a series of nozzles as hereinbefore described can be placed in a boiler in positions in which it would not be possible to insert rigid draw-off heads, the flexibility of the pipe permitting of its being pushed around angles or corners or beneath stays or other 75 obstructions.

The nozzles *d* can be slipped on to the pipes as shown in Fig. 3 and brazed or soldered in position, an aperture being cut in the said pipe opposite to each nozzle to allow the 80 liquid to enter the pipe. If desired, however, the nozzles can be connected by short lengths of pipe.

In a case where the suction pipe has to be introduced into a boiler in sections (as, for 85 instance, in the arrangement shown in Fig. 1) which are afterwards connected *in situ* it is necessary to employ angle connections, and I prefer that these connections should be combined with the nozzles. Such a combined nozzle and junction piece is shown at *d'* in Fig. 1 and is illustrated in an enlarged scale in Figs. 4, 5, 6 and 7. This fitting 90 comprises a socket *g* with a nozzle of the kind hereinbefore described, the said socket being 95 formed at the end with a clip piece *g'* into which the flange *i* of the bend *j* can be inserted, as clearly shown in Fig. 4, the two parts being subsequently united by a pin or bolt.

The ends of the pipe are advantageously provided with the single ended nozzles *d''* of the kind shown in Figs. 8 and 9.

In order to permit of introducing the sediment remover into a boiler of the kind shown 105 in Fig. 1, holes *k*, normally closed by covers *l* are provided at two of the angles, the lengths of pipe being inserted through the said holes and connected by a junction piece *d'* of the kind above described.

m is a fitting through which the draw-off is effected. This fitting is applied to the pipe

before the latter is introduced and is, as shown, internally screw-threaded, so that when it has been brought opposite to the aperture in the shell of the fire box it may be fixed by screwing into it a nipple π in a manner which will be clearly understood by reference to Figs. 10 and 11.

It will be understood that the arrangement of the fitting will be varied according to requirements to suit the particular boiler to which my invention is to be applied.

Having now particularly described and ascertained the nature of my said invention and in what manner the same is to be performed, I declare that what I claim is:—

1. An apparatus for removing sediment from steam boilers comprising a flexible tube, nozzles provided at intervals in said tube through which the sediment may be drawn and means for discharging the sediment outside of the boiler, substantially as described.

2. An apparatus for removing sediment from steam boilers comprising flexible tubing, a plurality of nozzles provided at inter-

vals in said tubing, said nozzles having inclined apertures, through which the sediment may be drawn from the boiler, and means for discharging same from the boiler, substantially as described.

3. An apparatus for removing sediment from steam boilers comprising flexible tubing, downwardly projecting nozzles provided on said tubing and adapted to support the same, whereby sediment may be drawn from the boiler and means for discharging same from the boiler, substantially as described.

4. A fire box for steam boilers provided with flexible tubing between the walls, nozzles provided on said tubing through which sediment may be drawn into the tubing, openings in the outer wall of the fire box to admit said tubing, closures for said openings and means for discharging the sediment from the tubing, substantially as described.

PERCY HULBURD,
